(57) **CLAIM**

We claim the ornamental design for scuba tank transport rack, as shown.

DESCRIPTION

FIG. 1 is an isometric view of the scuba tank transport rack design, looking toward the top and left sides;

FIG. 2 is a top plan view;

FIG. 3 is an elevational view of the left side;

FIG. 4 is an elevational view of the front end;

FIG. 5 is a bottom plan view;

FIG. 6 is an elevational view of the right side; and,

FIG. 7 is an elevational view of the back end.
